UNITED STATES PATENT OFFICE.

WILLIAM McMEANS, OF WEST LIBERTY, IOWA.

GRAIN ELEVATOR.

Application filed April 13, 1920. Serial No. 373,484.

To all whom it may concern:

Be it known that I, WILLIAM McMEANS, a citizen of the United States, residing at West Liberty, in the State of Iowa, have invented 5 certain new and useful Improvements in Grain Elevators; and I do hereby declare the following to be a full, clear, and exact description of the invention, such as will enable others skilled in the art to which it applies to make and use the same.

This invention relates to improvements in grain elevators more especially of the type for elevating grain into bins in storing the same.

15 The invention has for its object primarily the elevating of the grain as it is removed from the transporting or portable means, directly to the storing bins.

A further object is to provide for facilitating the locating of the grain-hauling or transporting means preliminary to elevating the grain therefrom.

A still further object is to provide for readily adjusting the grain elevating means 25 and the grain-hauling means with respect thereto, for storing the grain in the bins.

A still further object is to provide for carrying out these purposes in a simple, expeditious and effective manner.

30 Other objects of the invention will be apparent from the following description of the construction and operation thereof.

The invention consists therefore of certain instrumentalities and features of construction substantially as hereinafter more fully disclosed and defined by the appended claims.

40 The accompanying drawings illustrate the preferred embodiment or one form of my invention wherein it will be understood that various changes and modifications thereof as relate to the detailed construction and arrangement of parts may be made without departing from the spirit or scope of the invention as covered by the claims, and in which drawings—

Figure 1 is a side elevation of my invention, certain parts thereof also being shown in dotted or hatched lines.

45 Figure 2 is a like view thereof with the parts in inoperative position, the grain carrying means being outlined as when entering the portable driveway.

Figure 3 is a vertical section taken on the 55 line 3—3 of Figure 2.

Figure 4 is a plan or top view of my invention or elevator.

Figure 5 is a vertical transverse section taken on the line 5—5 of Figure 4.

Figure 6 is a front elevation of elevator in 60 extended or operative position.

Figure 7 is an enlarged fragmental view showing more particularly the grain receiving end of the elevator.

As characteristic features of my invention, 65 I provide a suitable frame-work designated generally as 1, which may be of general rectangular outline and of any suitable material construction, it may be of metal or wood, and which frame-work is preferably portably 70 mounted, as by means of rollers or trucks 2 preferably of relatively reduced diameter, and which frame-work may be termed as a drive-way for the purposes of my invention.

At one end of the frame-work or drive-way 1 is suitably provided a hoist 3 of the usual pivotal or swing-beam and block and tackle type, adapted particularly for tilting the grain-loaded wagon or conveyance as indicated in full and dotted lines in Figure 1, for dumping or transferring the grain contained therein into the elevator, as more fully presently made apparent. It will be understood that the grain-loaded wagon is driven within the frame-work or drive-way 80 and stopped with its tail-end adjacent outside the latter as seen in said Figure.

The elevator, designed generally as 4, includes endless belts of buckets 5 adapted to travel upon transverse bars 6 suitably secured to opposite longitudinal side-members 7 particularly as seen in Figure 3. The endless belts of buckets comprise articulated or hinged together links or strips 8 bearing or directly conveying the buckets 5 and encompassing, and are driven by sprocket pulleys or wheels 9 whose shafts 10, 10^a are suitably hung or journaled in bearings (not shown) within what is termed a "boot" 11, in this art at the entrance-end of the elevator and in 100 bearings at the opposite end of said elevator, respectively. The shaft 10^a is suitably supported in opposite bars, or supports 12 foldably mounted in position as seen in said Figures 1 and 2, the same being shown there-in as adapted to be adjusted in upright and depressed positions as more respectively fully disclosed hereinafter, consequently providing for the raising or lowering the shaft 10^a the purpose of which will be presently 110

seen. The shaft 10^a has a sprocket pulley 13 which is belted as at 14 to a like pulley 15 driven from a shaft 16, the latter being driven from a pulley 7 in practice belted to, 5 and driven from a conveniently disposed motor or other source of power for raising and lowering the shaft 10^a and accordingly the elevator proper or endless belts of buckets 5 for effecting the grain-elevation operation, in providing for lifting the grain into 10 a bin, the grain being delivered in the latter through a chute or spout 24 suitably attached to the upper end of the elevator.

The shaft 16, by means of which the 15 grain elevator is raised and lowered is received within, and bears partially within the hollow shaft 18 and partially upon the frame-work 1, the shaft 18, of course, bearing in like manner upon the shaft 16 and 20 upon said frame work. The supports 12 above referred to are attached to the shaft 18 and through it receive their foldable movement, the shaft 18, being provided with, and actuated preferably by a concave-toothed gear-wheel 19, meshing with a worm or spirally toothed shaft 20 suitably supported in position, and in practice, driven from a suitable source of power, said intergeared shafts, gear and worm mechanism 25 being disclosed in Figures 4, 5 and 6.

The elevator-boot 10, which is preferably suspended from an upwardly extending member 21 of the frame-work 1 at the forward end thereof, is adapted to be raised 30 and lowered, through block and tackle 22, as the elevator 4 is raised and lowered together with the tilting or dumping of the grain loaded wagon through the block and tackle 23 and swing beam of the hoist 3 into either of the dotted or full lined positions, as indicated in Figure 1.

Having thus described my invention what I claim is—

1. In a grain elevator, the combination of 45 a drive-way frame-work, an endless bucket elevating means, means for adjusting said elevating means into operative and inoperative position, means applied to the receiving end of said drive-way frame-work for initially transferring the grain to said elevating means, and means cooperative with said frame-work drive-way for tilting a grain loaded conveyance to discharge the grain into said initially transferring means said 50 bucket-elevating means having a member adapted to travel upon said frame-work and

adapted to cooperate with said initially grain transferring means as said grain elevator is actuated.

2. In a grain elevator, the combination of 60 an elevated drive-way frame-work, an endless bucket elevating means mounted upon said frame-work and provided at its receiving end with a "boot" to initially receive and transfer the grain to said elevating means, means for adjusting said elevating means into operative and inoperative position, and means for tilting a grain loaded conveyance to transfer the grain into said "boot".

3. In a grain elevator, the combination of 65 a drive-way frame-work, an endless bucket elevating means mounted upon said frame-work, means applied to the receiving end of said drive-way frame-work for initially receiving the grain, means for effecting the raising and lowering said grain initially receiving means and said endless bucket elevating means into operative and inoperative 70 position said endless bucket elevating means including a member adapted to travel upon said drive-way framework, and means for tilting a grain-loaded conveyance to transfer the grain to said grain initially receiving means.

4. In a grain elevator, the combination of 75 a drive-way frame-work, an endless bucket-elevating means mounted upon said frame-work, grain initially receiving means arranged at the receiving end of said drive-way frame-work, means for effecting the raising and lowering of said grain initially receiving means and said endless belt of buckets, means applied to the receiving end of said frame-work drive-way for tilting 80 the grain-conveying means to transfer the grain to said grain initially receiving means, and means for supporting the shaft of the outer end of said endless belt of buckets, foldably mounted upon said drive-way frame-work, additional shafts one being tubular and, having said shaft-foldable supporting means attached thereto, the other of said additional shafts extending through said tubular shaft and provided 85 with means cooperative to rotate the shaft of the endless belt of buckets and with means for driving the shaft extending through said tubular shaft.

In testimony whereof I affix my signature. 90

WILLIAM McMEANS.
